(57) **CLAIM**

I claim the ornamental design for the mascara container, as shown and described.

DESCRIPTION

FIG. 1 is a front view of a first embodiment of my design shown fully assembled.

FIG. 2 is an exploded view thereof.

FIG. 3 is a perspective view of the first embodiment of my design shown fully assembled.

FIG. 4 is an exploded view thereof.

FIG. 5 is a top view of the first embodiment.

FIG. 6 is a bottom view of the first embodiment.

FIG. 7 is a partial front view of the first embodiment illustrated with a magnified front view of the neck portion of the first embodiment designated in FIG. 2.

FIG. 8 is a perspective view of a portion of the first embodiment.

FIG. 9 is a front view of a second embodiment of my design.

FIG. 10 is a bottom perspective view of the second embodiment.

FIG. 11 is a top view of the second embodiment; and,

FIG. 12 is a bottom view of the second embodiment.

The fully assembled views of both embodiments are symmetrical about their axis. The dashed lines in FIGS. 2, 4, 7 and 8 illustrate portions of the article and form no part of the claimed design. All other surfaces or portions of my design not shown in the figures or otherwise described in the specification form no part of the claimed design.
